BOILER

Michael Zier and Edward M. Zier, New Albany,
Ind., assignors to Helen K. Zier and Rozine B.
Zier, both of New Albany, Ind.

Application April 11, 1931, Serial No. 529,434

3 Claims. (Cl. 122—166)

Our invention relates to new and useful improvements in water tube boilers and has for its principal object the provision of a boiler so constructed that all parts may be easily cleaned and replaced when necessary and in which the maximum amount of heat may be obtained from the use of a minimum amount of fuel.

Another object of our invention resides in the provision of a boiler of the character described in which an outer casing and inner chamber are provided, the water tubes extending through the heads of the inner chamber and communicating with the interior of the outer casing, and the heat being introduced directly into the inner chamber and into direct contact with the water tubes.

A further object resides in the provision of means whereby the heat is directed into the inner chamber or combustion chamber at a point above the surface of the lower head, this means allowing the heat to be directed into the chamber and into contact with the water tubes so as to secure the best results and to prevent burning out the lower head of the chamber.

A still further object consists in the provision of novel means for supporting a fuel bed and novel means whereby clinkers or ashes may be removed.

With the above and other objects in view, which will appear as the description proceeds, our invention consists in the novel details of construction, and arrangement of parts described in the following specification and illustrated in the accompanying drawing, and while we have illustrated and described the preferred embodiments of the invention, as they now appear to us, it will be understood that such changes may be made as will fall within the scope of the appended claims.

In the drawing:—

Fig. 1 is a side elevation.

Fig. 2 is a top plan.

Fig. 3 is a transverse vertical section with parts shown in side elevation, and

Fig. 4 is a horizontal section on the line 4—4 of Fig. 3 looking in the direction of the arrows.

In that form of our invention disclosed in Figs. 1 to 4 inclusive 1 indicates the outer casing and 2 the inner or combustion chamber so positioned within the outer casing as to provide a space around its side wall and beyond its heads to allow for the circulation of water within the casing. The outer casing includes the cylindrical side wall, the top head 3, and the bottom head 4, the bottom head being inset above the lower end of the casing as shown more particularly in Fig. 3 of the drawing. The bottom head 4 is provided with the manhole 5 normally closed by the plate or cap 6 and the top head is provided with the two manholes 7 normally closed by the plates or

caps 8. Water is introduced into the casing 1 through means of the pipe 9 and steam or water may be removed from the top of the casing by means of the pipe 10. At 11 we have illustrated a door normally closing an opening in the casing whereby clinkers may be removed from the fire bed when desired.

The inner or combustion chamber 2 consists of the circumferentially corrugated side wall 12, the top head 13, and the bottom head 14, the top head being provided with an opening 15 surrounded by the upwardly extending flange 16 in which is telescoped the depending flange 17 of the cap 18. A fuse plug 19 is provided in the cap 18 to act as a safety blow-off should the water within the casing 1 fall to a level below the upper surface of the cap 18. We wish to lay particular stress on the fact that the flange 16 and associated cap 18 provide an extending portion above the upper surface of the head 13 to prevent burning out of the head 13. As has been previously stated the fuse plug, being carried by the cap 18 will blow out when the water within the casing reaches a level below the top of the cap and thus prevents the water from reaching a level below the top head 13 of the chamber 2 which would cause the head to burn out. The bottom head 14 is provided with the opening 20 arranged off-center and positioned at a point adjacent the opening closed by the door 11 for a purpose which will be later apparent. Depending from the opening 20 is a sleeve 21 which leads to and communicates with an opening 22 formed in the bottom head 4 of the casing 1. The lower end of the sleeve 21 is secured to an upwardly extending flange 23 formed around the opening 22 and secured to the head 4 and depending therefrom is an air box or chamber 24 having an air inlet 25 to which, if desired, a fan may be attached. An inner sleeve 26 is positioned within the opening 20 formed in the head 14 and extending through this sleeve is the upper portion of a member 27 forming a part of or secured to an automatic stoker of any desired form. The member 27 is of such a diameter as to form the space 28 between the same and the sleeve 26 to provide an air passage and the upper end of the member has the outwardly extending flange 29 which will be spaced above the upper end of the sleeve 26 to provide an air passage. Perforations 30 are formed in the member 27 and allow air to pass to the interior of the member to allow proper burning of the fuel. The fuel is fed into the member 27 through the opening 31 of an extension which will pass through the side of the air box or chamber 24.

A vertically extending wall 32 extends from the bottom head 14 of the inner or combustion chamber 2 and terminates at a point below the upper head 13 as shown more particularly in Fig. 3 of the drawing. Vertically extending water tubes

33 are positioned within the chamber 2, on both sides of the wall 32 and their ends pass through the heads 13 and 14 to communicate with the interior of the casing 1. Thus water within the 5 casing 1 will circulate through these tubes. We wish to lay particular emphasis on the manner in which the tubes are arranged so as to form a space over the opening 20 in the bottom head 14 as shown more particularly in Fig. 4 of the 10 drawing. This space forms a clearance for the bed of fuel and the fuel will engage those tubes surrounding the space. At 34 I have shown a flue for taking off the products of combustion, the lower end of the flue communicating with the 15 chamber 2 as shown more particularly in Fig. 3 of the drawing.

At 35 we have shown the fuel, coal, which is fed into the member 27 by the stoker which forces the same upwardly through the member to provide the bed 36 at a point above the head 14 as shown more particularly in Fig. 3 of the drawing. This is of particular advantage for with the hot bed of fuel supported above the head and directly within the chamber 2 all heat is utilized 20 for heating the tubes and side wall of the chamber. At the same time, as previously stated, the hot bed of fuel will engage those tubes adjacent the bed and so aid in the heating. The products of combustion pass upwardly and over the 25 upper end of the wall 32 and then pass downwardly and out through the flue 34. Proper air is provided for causing the fuel to burn, such air entering the box or chamber 24, passing through the space 26, the space beneath the flange 29, 30 and through the perforations 28. With our construction and arrangement of manholes access may be had interiorly of the casing 1 and chamber 2 for cleaning purposes and for replacing parts which may be worn. The fuel bed is positioned at such a point relative to the opening 35 closed by the door 11 to permit ready removal of any clinkers which may form.

In our boiler it will be noted that the heat is introduced directly into the combustion chamber, above the upper surface of the lower head thereof, and directed against the water tubes. It will also be noted that the innermost water tubes are engaged by the bed or mass of fuel and form a support therefor. The sides of the combustion chamber are corrugated to add strength thereto but when desired stay bolts may be used. Our boiler may be used for any desired purpose, such as dairies or similar places where a large amount of steam is necessary, and, of course, we do not desire to be limited by such use. By introducing the heat directly with the combustion chamber above the upper surface of the lower head the life of the lower head will be prolonged and the head will not so readily be burned out.

Having fully described our invention what we claim as new and desire to secure by Letters Patent is:—

1. A boiler of the character described including an outer casing formed with a side wall and upper and lower heads, a separate and distinct combustion chamber formed with a side wall and upper and lower heads, the combustion chamber being positioned within the outer casing with its side wall and heads spaced from the side wall and heads of the casing and the heads of the combustion chamber having aligned openings positioned off center, a door carried by the outer casing and adapted to normally close an entrance opening to the combustion chamber, said entrance

opening being positioned in close proximity to the opening in the lower head of the combustion chamber, water tubes positioned between the heads of the combustion chamber and surrounding the openings in the heads thereof with the exception of a space aligned with the entrance opening, a member positioned in the opening of the lower head of the combustion chamber for supporting a bed of fuel above the lower head whereby heat is generated directly in the combustion chamber above the lower head thereof and into direct engagement with the water tubes surrounding the opening, a cap positioned above the upper head of the combustion chamber and normally closing the opening therein, and a fuse plug carried by the cap.

2. A boiler of the character described including an outer casing formed with a side wall and upper and lower heads, a separate and distinct combustion chamber formed with a side wall and upper and lower heads, the combustion chamber being positioned within the outer casing with its side wall and heads spaced from the side wall and heads of the casing and the lower head of the combustion chamber having an opening positioned off center, a door carried by the outer casing and adapted to normally close an entrance opening to the combustion chamber, said entrance opening being positioned in close proximity to the opening in the lower head of the combustion chamber, water tubes positioned between the heads of the combustion chamber and surrounding the opening in the lower head thereof with the exception of a space aligned with the entrance opening, a member positioned in the opening of the lower head of the combustion chamber for supporting a bed of fuel above the lower head whereby heat is generated directly in the combustion chamber above the lower head thereof and into direct engagement with certain of the water tubes surrounding the opening, means for conveying spent heat from the combustion chamber, and a baffle wall positioned in the combustion chamber between the bed of fuel and the means for conveying the spent heat.

3. A boiler of the character described including an outer casing formed with a side wall and upper and lower heads, a separate and distinct combustion chamber formed with a side wall and upper and lower heads, the combustion chamber being positioned within the outer casing with its side wall and heads spaced from the side wall and heads of the casing and the lower head of the combustion chamber having an opening positioned off center, a door carried by the outer casing and adapted to normally close an entrance opening to the combustion chamber, said entrance opening being positioned in close proximity to the opening in the lower head of the combustion chamber, water tubes positioned between the heads of the combustion chamber and surrounding the opening in the lower head thereof with the exception of a space aligned with the entrance opening, and a member depending through the opening of the lower head of the combustion chamber for supporting a bed of fuel above the lower head whereby heat is generated directly in the combustion chamber above the lower head thereof and into direct engagement with the water tubes surrounding the opening, said member positioned in the opening to provide an air space therearound.
